UNITED STATES PATENT OFFICE.

HARRY GEORGE SPOONER STONE AND LEON REES, OF LONDON, ENGLAND.

DESIGN FOR A TOY ANIMAL.

Application filed April 24, 1922. Serial No. 1,929. Term of patent 7 years.

To all whom it may concern:

Be it known that we, HARRY GEORGE SPOONER STONE and LEON REES, subjects of the King of Great Britain, residing at London, England, have invented a new, original, and ornamental Design for a Toy Animal, of which the following is a specification, reference being made to the accompanying drawings, forming part thereof.

Fig. 1 is a front elevation of a toy animal embodying the features of the design; and

Fig. 2 is a side elevation of the same.

We claim:—

The ornamental design for a toy animal as shown.

HARRY GEORGE SPOONER STONE.
LEON REES.
